UNITED STATES PATENT OFFICE.

OTTO BARK, OF CHICAGO, ILLINOIS.

SHEET-METAL-TUBE-FORMING MACHINE.

1,365,019.

Specification of Letters Patent. Patented Jan. 11, 1921.

Application filed March 5, 1920. Serial No. 363,536.

To all whom it may concern:

Be it known that I, OTTO BARK, a citizen of the United States of America, and a resident of Chicago, county of Cook, and State 5 of Illinois, have invented certain new and useful Improvements in Sheet-Metal-Tube-Forming Machines, of which the following is a specification.

The main objects of this invention are to 10 provide an improved machine for making sheet-metal tubing; to provide a machine having improved means for forming the tubing from two sheets of metal; to provide improved means for properly spacing apart 15 the sheets of metal from which the tube is formed whereby said tube will be of the desired cross section; to provide improved means for corrugating the tube transversely of its length as it is formed; and to provide 20 an improved machine of this kind which is particularly adapted for use in forming sheet-metal tubing of narrow elongated cross section to be used in the construction of radiators for water cooled devices. 25

An illustrative embodiment of this invention is shown in the accompanying drawings, in which—

Figure 1 is a diagrammatic plan partly 30 broken away of a machine constructed in accordance with this invention.

Fig. 2 is a side elevation of the same.

Fig. 3 is a transverse sectional detail 35 taken on the line 3—3 of Fig. 2, the parts in the background being omitted.

Fig. 4 is a similar view taken on the line 4—4 of Fig. 2.

Fig. 5 is an enlarged fragmentary detail of the interfitting parts of the rolls.

Fig. 6 is an enlarged sectional detail of 40 a form of sheet-metal tubing which the particular modification herein shown is designed to produce.

Although this invention is not limited to 45 that particular purpose, the modification herein illustrated and described has been designed for use in the formation of tubing of the type shown in my copending application Serial No. 329,394, filed Oct. 8, 1919, 50 which tubing is to be used particularly for the manufacture of radiators for cooling the circulating water used in connection with internal combustion engines and the like.

In the specific embodiment herein diagrammatically illustrated, the device comprises a pair of rolls 7 and 8 and a core

member or mandrel 9 arranged to form two strips of metal 10 and 11 into a sheet-metal tube 12.

The rolls 7 and 8 have their peripheries 60 shaped to provide axially disposed corrugations 13 and are mounted on shafts 14 and 15 so as to be rotated at uniform speeds by suitable gearing (not shown). The mounting of the shafts 14 and 15 is such that the 65 peripheries of said rolls are properly spaced apart to coact with the core member or mandrel 9 in the shaping of the strips of metal 10 and 11 to a tube 12 of the desired cross section. Grooves 16 and 17 are circumferentially 70 formed in the periphery of the rolls 7 and 8 respectively near the ends thereof, which grooves are adapted to coact to form the seams in a tube, as will more fully hereinafter appear. 75

The core member or mandrel 9 is of a flexible nature being constructed from heavy woven cotton canvas, woven metal fabric or a combination of the two. As herein shown, a strip of the flexible material is looped 80 through a slot 18 formed in a plate 19 extending rearwardly from the rolls 7 and 8 and secured to a block or bar 20 mounted on the frame of the machine. The width and the thickness of the flexible material is made 85 so as to give the desired shape to the tube 12.

The strips of sheet-metal 10 and 11 are cut and shaped by other means before being fed to the rolls 7 and 8. In this particular case, the sheet 10 has had the edges thereof 90 curled around reinforcing wires 21 and then bent to provide flanges 22. The strip 11 has its edges turned so as to provide the flanges 23. Suitable means are provided for feeding the sheets 10 and 11 to the rolls 7 and 8 95 in such a way that as said strips approach the rolls, the flanges 22 pass into engagement with the flanges 23 inwardly thereof.

The operation of the machine as herein illustrated, is substantially as follows: 100

By suitable mechanism, the strips of metal 10 and 11, previously shaped, are fed to the rolls 7 and 8. As said strips approach the rolls, the pairs of flanges 22 and 23 enter into engagement as has just been explained, 105 and upon entering the grooves 16 and 17 of the rolls 7 and 8, are bent over and firmly compressed together to form a substantially water-tight seam along the edges of the tube. As the strips pass between the rolls 7 110 and 8 and are seamed together, they are given a corrugated formation, as shown to

the right of Fig. 2. The core member or mandrel 9 being held stationary and the feeding pressure of the rolls being upon the lateral seamed edges of the tube, the metal strips readily drag over said core member or mandrel and leave the same with the opposite sides of the tube properly spaced apart.

Although but one specific embodiment of this invention has been herein shown and described, it will be understood that numerous details of the construction shown may be altered or omitted without departing from the spirit of this invention as defined by the following claims.

I claim:

1. In a machine for forming flat tubing, the combination of a pair of opposed rolls having their peripheries spaced apart and a stationary flexible core member arranged between said rolls, said rolls being adapted to have fed between them on opposite sides of said core member strips of metal having flanges formed along the edges thereof, said rolls having their peripheries shaped so as to coact with said core member and with each other to form said strips into a tube of elongated cross section with said flanges compressed into seams along the edges of said tube.
2. In a machine of the class described, the combination of a pair of rolls having their peripheries specially shaped and spaced apart and a stationary flexible core member arranged between said rolls, said rolls and core member coacting to form a sheet-metal tube of predetermined shape and cross section.
3. In a machine of the class described, the combination of a pair of opposed rolls having their peripheries spaced apart and provided with axially disposed corrugations, a stationary flexible core member arranged between said rolls, said rolls being adapted to have fed between them on opposite sides of said core member sheet-metal strips, said rolls and core member coacting to form said sheets into a corrugated sheet-metal tube of predetermined cross section.

4. In a machine for forming flat corrugated tubing, the combination of a pair of rolls having the peripheries thereof spaced apart and provided with axially disposed corrugations, to which rolls are adapted to be fed strips of metal having flanges formed along the edges thereof, said rolls having their peripheries constructed circumferentially so as to coact with said corrugations in shaping said strips into a corrugated tube of the predetermined cross section and to form said flanges into seams.

5. In a machine of the class described, the combination of a pair of opposed rolls having their peripheries specially shaped and spaced apart, a canvas core member arranged between said rolls, a support arranged at one side of said rolls in substantial alinement with the space between them and connected to said core member, said rolls being adapted to have fed thereto on opposite sides of said core member strips of metal having flanges formed along the edges thereof, said rolls and core member coacting to form said sheet into a sheet metal tube of predetermined shape and cross-section, with said flanges compressed into seams along the edges thereof.

6. In a machine of the class described, the combination of a pair of opposed rolls having their peripheries specially shaped and spaced apart, a core member arranged between said rolls, a support located at one side of said rolls and a connection to said support from said core member adapted to maintain the core member in substantially fixed alinement with a space between said rolls, said connection being so mounted that the space on all sides thereof rearwardly of said rolls is substantially unobstructed, whereby said rolls are adapted to have fed thereto on opposite sides of said core sheets of metal of substantially unlimited lengths, said rolls and core coacting to form said sheets into a sheet-metal tube of the desired shape and cross section.

Signed at Chicago this 13th day of February 1920.

OTTO BARK.
